UNITED STATES PATENT OFFICE

RALPH O. HELGEBY, OF FLINT, MICHIGAN, ASSIGNOR TO A C SPARK PLUG COMPANY, OF FLINT, MICHIGAN, A COMPANY OF MICHIGAN

SPEEDOMETER

Application filed August 20, 1928. Serial No. 300,847.

This invention relates to magnetic measuring instruments and has been designed more particularly to provide an improvement in a fixed magnet type of speedometer for vehicles.

An object of the invention is to provide a clamping means by which a U-shaped magnet may be quickly mounted on the instrument frame. Simplicity, efficiency, convenience in assembly and economy are among the objects sought to be attained.

In the drawing:

Figure 1 is a top plan view of a speedometer employing a permanent fixed magnet held in position by my novel clamping means;

Figure 2 is a side elevation of the same; and Figure 3 is a perspective of the clamp.

Referring by reference characters to the several figures of the drawing, numeral 15 designates an instrument frame for carrying the parts constituting the speed indicating mechanism. It is also designed to carry the odometer mechanism, although the latter is in no way concerned with this invention. The

frame is preferably die cast. It may be formed with a bearing 21 for the reset stem of the odometer. Across the top of the frame is a jewel frame 22 secured by suitable fastening means 23 to the main frame 15. At 24 is

a conventional speed cup, its zero reading being assured by hair spring 25. This hair spring is operatively associated with a spindle, not shown, carrying the speed cup and with an arm 26 on an adjustable regu-

lator 27, which is rotatable about an upper bearing carrier 28 for the said spindle. The jewel frame 22 has stamped therefrom a part 22' positioned over the said spindle to retain the same from axial movement. The

lower bearing for the spindle is, as is customary in such constructions, located in the upper end of the rotor shaft, not shown. This rotor shaft is mounted in the frame 15 and is, as usual, driven by a flexible shaft,

not shown. The rotor shaft as usual terminates in a rotor located within the speed cup.

A magnet 14 surrounds the speed cup, rests upon and is clamped to the frame. To hold the magnet in position, there is used the novel attachment which constitutes the subject of

this application. This attachment comprises a clamp designated as a whole by numeral 9, the clamp being preferably made as a stamping. The clamp is provided with legs 10 and 11, which are angularly turned as at 12 and 13 to form fingers at their ends designed to grip the upper edge of the magnet. The clamp also has a leg 16 which has an opening 17 for a screw 18, which is threaded into the frame to thereby hold the magnet in position. The end of leg 16 is angularly bent as at 18' to engage the frame. When the screw 18 is tightened, it draws up the magnet firmly into position on the frame, the legs 10 and 11 being arcuately bent to engage the peripheral surface of the magnet and the fingers 12 and 13 gripping the upper edge thereof to restrain the magnet from movement.

There has thus been designed a simple, effective clamp of substantially Y-shape. This clamp is economical to manufacture and it provides for an easy assembly of the U-shaped magnet on the die cast frame.

I claim:

1. In a measuring instrument, a frame, a U-shaped magnet supported adjacent the ends of its legs on said frame and the end faces of said legs engaging said frame, a clamp of substantially Y-shape, two legs of said clamp embracing said magnet between its ends, a third leg abutting said frame, and fastening means engaging a middle part of said clamp and adjustably secured to said frame.

2. The invention defined by claim 1, said first-mentioned legs having angularly positioned terminal fingers engaging the upper surface of said magnet.

3. The invention defined by claim 1, said first-mentioned legs being of arc shape to conform to the shape of said magnet and having angularly positioned terminal fingers engaging the upper surface of said magnet.

In testimony whereof I affix my signature.

RALPH O. HELGEBY.
